CLAIM

We claim the ornamental design for portable information handling system housing, as shown and described.

DESCRIPTION

FIG. 1 is a rear lower perspective view of the portable information handling system comprising the present invention;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof;

FIG. 8 is a front perspective view in an open position thereof;

FIG. 9 is a rear upper perspective view thereof; and,

FIG. 10 is a rear upper perspective view in an open position thereof.

Broken lines shown in the drawings illustrate portions of the portable information handling system housing, and form no part of the claimed design. The dot dash broken lines show boundaries of the claimed design and form no part thereof.

1 Claim, 8 Drawing Sheets
